A. S. TRUE.

COMBINATION ARBOR PRESS.
APPLICATION FILED OCT. 25, 1916.

1,251,136.

Patented Dec. 25, 1917.

UNITED STATES PATENT OFFICE.

AUGUSTUS S. TRUE, OF ARLINGTON, MASSACHUSETTS, ASSIGNOR TO CRANE PULLER COMPANY, OF ARLINGTON, MASSACHUSETTS, A CORPORATION OF MASSACHUSETTS.

COMBINATION ARBOR-PRESS.

1,251,136.

Specification of Letters Patent. Patented Dec. 25, 1917.

Application filed October 25, 1916. Serial No. 127,611.

To all whom it may concern:

Be it known that I, AUGUSTUS S. TRUE, a citizen of the United States, residing at Arlington, in the county of Middlesex and

5 State of Massachusetts, have invented new and useful Improvements in Combination Arbor-Presses, of which the following is a specification.

The object of the present invention is to 10 provide a base adapted to be used in combination with a tool now in general use, to provide an arbor press. The tool with which such base is adapted to be combined is commonly known as the Crane puller, 15 and is the basis of Letters Patent 724,818, granted April 7, 1903. It is estimated that there are at the present time about fifty thousand or sixty thousand Crane pullers in use, a large number of which are used 20 in automobile repair shops and in general machine shops. The Crane puller has proved to be an extremely useful tool for some kinds of work, but it has not hitherto been generally useful for bench work.

25 The present invention provides a base adapted to be affixed to a work bench, and may remain permanently on the bench, said base having provisions for having a Crane puller coupled to it so that the two devices 30 in combination with each other will provide an effective arbor press. The base is preferably made in such form that a vehicle wheel, for example, may be placed upon it before the "puller" has been coupled to it, 35 and has provisions adapted to enable the hook-shape links of the "puller" to be moved laterally into hooked relation therewith after the links have been inserted into diametrically opposite spaces between the 40 spokes of the wheel. When the base, "puller", and a vehicle wheel are assembled as above stated, the arbor press is usable for forcing ballraces or other elements into or out of the hub of the wheel. To be thus 45 enabled to operate upon a wheel with a press of much smaller dimensions than the wheel is a great advantage, particularly as the "puller" is readily detachable from its base, and may be used independently of the base, 50 while the base is usable for some purposes independently of the "puller."

The invention therefore comprehends primarily the combination of a base with the well known "puller" above identified; but 55 inasmuch as the base is capable of manufac-

ture, use and sale, independently of the "puller," the invention comprehends also such base *per se* as an article of manufacture, use and sale.

Of the accompanying drawings:

Figure 1 represents a top plan view of a base embodying the present invention, and includes the links of a Crane puller, in section, in coöperative relation thereto. The base is shown as being mounted upon a 65 bench.

Fig. 2 represents a front elevation, partly in section, of the assemblage, including a bench, the base mounted thereon, and a Crane puller in coöperative relation to the 70 base.

The same reference characters indicate the same parts wherever they occur.

I will describe first the characteristic features of the well known Crane puller. This 75 device comprises a screw 10 and nut 11 adapted to coact. The nut has arms 12, 12 that extend laterally in opposite directions, and said arms are provided with holes 13 each of which is adapted to receive a pivot 80 member. Links 15, 15 are connected to the arms 12, 12 by pivot members 14, 14 and are capable of being adjusted toward and from the screw 10 by shifting the pivot members 14, 14 from one hole 13 to another. 85 The free ends of the links have hooked portions 16. All the above-specified structural features of the "puller" are disclosed in the said Patent 724,818, excepting that in the present instance the holes 13 are substituted 90 for the notched slots shown in the patent. This difference, however, is immaterial so far as the present invention is concerned.

The base hereinbefore referred to is indicated at 20. It is adapted to be mounted 95 upon and affixed to a bench such as that indicated at 21, and for this purpose is provided with bolt-receiving holes 22. When clamping bolts 23 are inserted through the holes 22 in the base and through registering holes (not shown) in the bench 21, and clamped tightly by nuts such as that indicated at 24 in Fig. 2, the base is rigidly secured to the bench, and is preferably arranged in such relation to the edge 25 of 100 the bench as to overhang such edge and leave a clear space below the overhanging portion for shafts, axles, or other objects upon which the press may be used to operate.

For convenience of description the ever- 110

hanging portion of the base is indicated at 26. A work-receiving recess 27 is formed in such overhanging portion, and a rotatable disk 28 is connected to the base by a pivot 5 member 29 in such relation as to overhang the portion in which the recess 27 is formed. The disk 28 is provided with a plurality of notches 30 of various sizes each of which may be brought into register with recess 27 10 by turning the disk, and the latter serves as an anvil or support for the object to which pressure is to be applied.

The base is provided with sockets or recesses 31 adapted to receive the links 15 of the "puller." These sockets or recesses are preferably open at the front of the base, as indicated at 32, to enable the links 15 to move laterally into them and out of them. When the links are arranged in the recesses 20 31 the hook portions 16 are adapted to underlie and coact with the edge portions 33 of the base, to sustain whatever upward stress is applied to the links in consequence of downward stress of the screw 10 upon an 25 object lying upon the anvil 28.

In order to prevent the links 15 from being dislodged accidentally from the sockets or recesses 31, the base is provided with retaining portions 34, 34, behind which portions 30 of the links 15 may be arranged as shown by Fig. 1. Then, in order to prevent the links from being dislodged from the retaining portions 34, the base is provided with setscrews 35 adapted to be set up 35 against the links. When the setscrews are set up tightly against the links, the weight of the "puller" is sustained by the clamping action so produced, and the "puller" and base become, to all intents and purposes, a 40 rigid unit. In order to permit detaching the "puller" from the base the setscrews need be unscrewed only far enough to enable the links 15 to pass around the retaining portions 34 and through the openings 32. The 45 base and "puller" may therefore be assembled and taken apart very quickly.

When the "puller" is detached from the base the latter is useful for other bench jobs, such as driving out rivets, tight-fitting bolts, or other objects.

Although I have explained how the "puller" and base may be used in combination with each other for forcing a ball-race into or out of the hub of a wheel, it is apparent that such combination is capable of very many other uses which it will not be necessary to state.

I claim:

1. In combination, a nut and screw 60 adapted to coact, said nut having arms extending laterally in opposite directions, links pivotally connected to said arms, and

a work support having edges arranged to coact with the free ends of said links, said ends having hook portions adapted to engage said edges to sustain the stress caused by said screw, said links being detachable from said work support. 65

2. In combination, a nut and screw adapted to coact, said nut having arms extending laterally in opposite directions, links pivotally connected to said arms, a work support having recesses adapted to receive portions of said links, said links having hook portions adapted to engage said 75 work support to sustain the stress caused by said screw, said links being removable from said recesses, and means arranged to confine said links in said recesses to keep them anchored to said work support. 80

3. In combination, a nut and screw adapted to coact, said nut having arms extending laterally in opposite directions, links pivotally connected to said arms, a work support having recesses adapted to receive portions of said links, said recesses having openings adapted to permit lateral insertion and removal of the links, said links having hook portions adapted to coact with said work support, and means adapted 85 to confine said links in said recesses to keep them anchored to said work-support. 90

4. The herein-described article of manufacture, comprising a base having marginal portions arranged to afford anchorage for 95 the hook-portions of a "puller", adjustable members carried by said base and arranged to bear against such hook-portions to confine the latter in anchored relation to said marginal portions, said base having portions arranged to confine such hook-portions in coöperative relation to said adjustable members. 100

5. The herein-described article of manufacture, comprising a base having oppositely 105 disposed edge portions arranged to afford anchorage for the hook portions of a "puller", and setscrews carried by said base and arranged to bear against such hook portions to confine the latter against dislodgment from anchored relation with said base. 110

6. The herein-described article of manufacture, comprising a base having oppositely disposed recesses adapted to receive laterally movable hook portions of a "puller", and having shoulders arranged to confine such hook portions against lateral dislodgment from said recesses, and means adapted to keep such hook portions behind said shoulders, substantially as described. 115 120

In testimony whereof I have affixed my signature.

AUGUSTUS S. TRUE.
